UNITED STATES PATENT OFFICE.

ADAM LOEB, OF PORTLAND, OREGON.

SHELL FOR CARTRIDGES.

957,171.

Specification of Letters Patent. Patented May 3, 1910.

Application filed December 14, 1908. Serial No. 467,559.

To all whom it may concern:

Be it known that I, ADAM LOEB, a citizen of the United States, and a resident of Portland, in the county of Multnomah and State of Oregon, have invented a certain new and useful Improvement in Shells for Cartridges, of which the following is a specification, reference being had to the accompanying drawings as constituting a part thereof.

This invention has for its object to cause the igniting flash produced by the cap of the cartridge to travel from the center of the base of the powder charge radially and simultaneously forward to the whole cross section area of the main body of the powder charge; and I accomplish my object by providing the butt end of the cartridge with a conical flash chamber. That is, the powder space at the butt end of the cartridge being tapered downward to the central cap-hole in the butt end of the cartridge. By such arrangement is avoided the waste of energy during the interval that the flash, under ordinary conditions, would travel laterally and backward; for by my improved construction the path of the flash is confined to a radial and forward direction, and communicates the igniting flash simultaneously to the entire cross-section area of the main body of the powder.

The result obtained by my improvements are: The quantity of powder at present used in the common straight shell may be reduced without diminishing the degree of force of penetration imparted to the projectile, compared with that obtained from a normal charge of powder; or, by using the present standard unit or quantity of powder in my improved cartridge, the force of penetration is greatly increased. In my experiments, I have found this increase in the force of penetration to be as great as two-thirds over the degree of penetration obtained from the same quantity of powder used in a common straight shell. Furthermore, by reason of eliminating the backward movement of the igniting flash in the base of the powder charge, the recoil of the gun is diminished.

My improvement can be added to any common form of shell by merely inserting, in

the base thereof, a block adapted to be placed over the cap in the base of the cartridge, and provided with a cuneate central chamber, and having a flash aperture registering with the cap.

Referring now to the drawings as illustrating more clearly the application of my invention: Figure 1 is a sectional elevation of a common straight-side cartridge, to which my improvement is added by inserting in the base thereof a block provided with a cuneate central flash chamber having a flash aperture registering with the cap; Fig. 2 is a top view of the shell shown in Fig. 1, with the shot and powder thereof removed; and Fig. 3 is a sectional elevation, showing a modification in this, that the base of the shell itself is made with tapering walls, centering in a central flash aperture registering with the cap, inserted in the base of the cartridge.

Having reference now to the letters in the several views, and referring in the first instance to Figs. 1 and 2: the shell, *g*, is of the common straight-side type, and is adapted to have a cap, *b*, inserted in the base thereof. Within the shell, at the base, is inserted a block, *c*, provided with a cuneate or tapering flash chamber, *d*, centering in an aperture *e*, at the base, which flash aperture registers with the cap *b*. The block *c* may be made of paper, or other suitable material. In order to adapt the block, *c*, to be placed over the cap, as shown in Fig. 1, the bottom thereof is made with a cavity *f*, whereby the block is adapted to be placed over the cap *b*. It will now be apparent that the instant the flash reaches the base of the flash chamber, *d*, and ignites the powder therein contained, such flash must travel simultaneously in a radial and forward direction to the whole cross section area of the main body of the powder charge.

In the modification shown in Fig. 3, the shell, *g*, is provided at the base with a contracted wall-portion, *h*, tapering downward to a central flash aperture, and being adapted to have a cap, *i*, inserted in the base of said flash aperture, as shown. The flash chamber, *j*, produces the same effect, obviously, as the chamber *d*, above described.

p, p' in Figs. 1 and 3 represent the powder charge.

I claim:

5 A cartridge shell formed of a thin material open and comprising a cylindrical body portion tapered at one end to form a conical inner flaring chamber, and a cylindrical re-

duced portion open at its outer end and projecting outwardly from the tapered end.

ADAM LOEB.
